CAR WASHING MACHINE

Clyde P. Ross, Kenilworth, Ill., assignor to Ross and White Company, Chicago, Ill., a corporation of Illinois

Application March 31, 1933, Serial No. 663,717

6 Claims. (Cl. 15—53)

This invention relates to washing machines, and has to do with a machine for washing cars and like vehicles.

It is known to provide two washing machines disposed at opposite sides of a track along which a car passes and is subjected to a washing operation as it passes between the machines. This necessitates the use of two machines, which are rather expensive, and the time saved in washing a car does not offset the expense incurred in the provision of two machines.

One of the main objects of my invention is to provide a washing machine which, when disposed between two tracks, can be adjusted so as to wash the side of a car traveling in either direction upon either track. In this manner, I render it possible to wash a car with a single machine, thus eliminating the expense incident to the provision of two machines in accordance with the present practice. While my machine is preferably adjustable so as to wash a car traveling in either direction upon either track, this is not essential to the broad concept of my invention, which comprehends broadly the provision of a machine capable of being disposed between two adjacent tracks and adjustable so as to wash a car traveling upon either track. A further object of my invention is to provide a machine having brushes for washing the body of the car, these brushes being automatically adjustable to accommodate transverse tilting of the car being washed. It is also an object of my invention to provide improved means for driving the brushes of the machine. Further objects and advantages of my invention will appear from the detail description.

In the drawings:—

Figure 1 is a side view of a car washing machine constructed in accordance with my invention;

Figure 2 is a section taken substantially on line 2—2 of Figure 1, on an enlarged scale, parts being shown in elevation;

Figure 3 is a section taken substantially on line 3—3 of Figure 1;

Figure 4 is a semi-diagrammatic view, broken away and partly in section, illustrating the use of two machines, constructed in accordance with my invention, for washing a car;

Figure 5 is a section taken substantially on line 5—5 of Figure 4, the washing mechanisms and the car being washed being shown in elevation;

Figure 6 is a diagrammatic view illustrating the

adjustability of the body brushes to accommodate tilting of the body of the car;

Figure 7 is a diagrammatic view illustrating the use of the machine of my invention when disposed between two adjacent tracks for washing one side of a car travelling upon one track and the opposite side of the car when travelling upon the other track;

Figure 8 is a diagrammatic view similar to Figure 7, on a reduced scale, and showing the switches for transferring the car from one track to the other;

Figure 9 is a sectional view, on an enlarged scale, with parts broken away and parts shown in elevation, through the upper portion of the machine comprising the upper arms of the brush carrying frames and associated parts;

Figure 10 is a view similar to Figure 9 through the lower arms of the brush carrying frames and associated parts.

The machine comprises a support 1 conveniently in the form of a tubular column formed from lengths of tubing disposed in telescoping relation and welded or otherwise suitably secured together. A bell member 2 is suitably secured to support 1 as by means of dog pointed set screws 3, and engages beneath a shoulder 4 formed on the support 1 by slightly reducing the exterior diameter thereof. Member 2 seats upon a thrust ring 5 which seats in the upper face of a worm wheel 6, the latter seating in the upper end of a cylindrical base 7, to which the gear 6 is secured by dowel pins 8. Base member 7 comprises reinforcing webs 9 and a base flange 10 adapted for bolting to a suitable foundation 10a. The lower end portion 30 of support 1 fits snugly within the body of base member 7 and is supported by bell member 2 and associated parts for rotation on a vertical axis. The skirt portion of bell member 2 carries a shaft 11 rotatably mounted therein, and a worm gear 12 is secured upon this shaft and meshes with worm wheel 6, the latter being fixed to the base member. A hand wheel 13 is secured upon the outer end of shaft 11 for rotating the latter in desired direction. The worm gear 12 and worm wheel 6 provide means for rotating support 1 and locking it in desired adjustment.

A main frame is pivotally mounted on support 1 for movement on an axis parallel with the axis of rotation of the support. This frame comprises an upper arm 14 and a lower arm 15, these arms conveniently being of channel cross-section. A bearing box 16 (Figure 9) is secured to arm 14 adjacent support 1 and receives a bushing 17 extending upwardly from a bearing box 18 bolted

20

25

30

35

40

45

50

55

to a channel bracket 19 welded or otherwise suitably secured to support 1 adjacent the upper end thereof. Bushing 17 is provided with a shoulder 20 which contacts the lower end of bearing box 16 for supporting the arm 14 which is thus pivotally mounted on the bracket 19. A shaft 21 is rotatably mounted through a flanged bushing 22 extending into the upper end of bushing 17 with its flange seating upon the upper end of the latter. This shaft extends downwardly through bracket 19 and into a bushing 23 seated in the upper end of a bearing box 24 bolted to a channel bracket 25 which is welded or otherwise suitably secured to support 1. A shaft 26 extends into the lower portion of bearing box 24 and thence downwardly through a bearing box 27 bolted or otherwise suitably secured to upper arm 28 of a secondary frame, this arm preferably being of channel cross-section. A thrust collar 29 is secured upon the shaft and contacts the lower end of bearing box 27. A sleeve 30 is disposed about shaft 26 concentrically therewith and is secured to the shaft by means of annular plugs 31 disposed in the ends of the sleeve and welded thereto and to the shaft. Shaft 26 extends downwardly beyond sleeve 30 (Figure 10), through the web element of lower arm 32 of the secondary frame, which arm is preferably of channel cross-section, and through a bearing box 33 suitably secured to this arm. The shafts 21 and 26, and associated parts, provide means whereby the upper arm 14 of the main frame and the upper arm and the lower arm of the secondary frame are pivotally mounted for movement about a common axis, it being noted that this axis is coincident with the axis of shaft 21.

A bearing box 34 is bolted or otherwise suitably secured to a channel bracket 35 welded to support 1 at the lower portion thereof. This box 34 receives the lower end of shaft 26 and the upper end of the box provides a seat for the lower end of a worm wheel 36 suitably secured on the shaft. This worm wheel is disposed within a gear housing 34a formed integrally with the bearing block 34 and meshes with a worm 37 secured on a shaft 38 rotatably mounted in the housing 34a, a hand wheel 39 being secured on the outer end of this shaft for rotating the latter in desired direction. A housing cover 40 is mounted on shaft 26 and is confined between the upper end of the hub of worm wheel 36 and a thrust collar 41 upon which the lower end of bearing block 33 rests. The shaft 26 and the secondary frame and associated parts are thus supported by bracket 35, arms 28 and 32 of the secondary frame being movable about shaft 26, and the latter and sleeve 30 being rotatable independently of the secondary frame by means of worm wheel 36 and worm 37, the worm wheel 36 and worm providing means for rotating sleeve 30 and locking it in adjustment.

A bearing box 42 is bolted or otherwise suitably secured to the web portion of lower arm 15 of the main frame, this arm preferably being of channel cross-section. A stub shaft 43 extends through bearing box 42 and into a bearing box 44 bolted or otherwise suitably secured to a lower channel bracket 45 welded to support 1 below bracket 35. Bearing box 44 preferably contains self-aligning roller bearings of known type into which the lower portion of stub shaft 43 extends, and a thrust collar 46 is disposed between the lower end of box 42 and the upper end of box 44. Stub shaft 43 is disposed coaxially with shaft 26 so that the main frame and the secondary frame

are pivotally mounted for movement on a common axis parallel with the axis of rotation of support 1.

The main frame carries a brush structure comprising a tubular brush shaft 50 and upper and lower brushes 51 and 52 secured upon this shaft in a suitable manner, these brushes being spaced to contact the side of a car above and below the windows and of a length to extend from the windows to the eaves and from the bottoms of the windows to the bottom of the car body. A stub shaft 53 (Figure 10) is secured in the lower end of shaft 50 and is provided with a shoulder 54 upon which the lower end of shaft 50 rests. Shoulder 54 rests upon a thrust collar 55 disposed about stub shaft 53 and seating upon a self-aligning roller bearing structure 56 of known type mounted in a bearing box 57 bolted or otherwise suitably secured to lower arm 15 of the main frame, adjacent the outer end of this arm. The upper end of shaft 50 is connected by a universal joint 58, of known type, to a stub shaft 59 rotatably mounted in self-aligning roller bearings of known type, which bearings are mounted in a bearing box 60 bolted to the outer end of upper arm 14 of the main frame. The provision of the universal joint 58 in the brush shaft of the main frame, in conjunction with the independent pivotal mounting of the arms 14 and 15 of this frame, permits of limited relative movement between these arms so that the brushes 51 and 52 can accommodate slant of the side of the car due to transverse tilting thereof, which is not uncommon. In the use of the machine, the main frame extends lengthwise of the car at an inclination thereto and in the direction of travel thereof. If the tilt of the car is toward the apparatus, so that the panel of the body above the windows is somewhat nearer the apparatus than the panel below the windows, the brush structure of the main frame may incline to the left and upwardly as indicated by the dotted line position in Figure 6. If the tilt of the car is in the opposite direction, the brush structure of the main frame will be inclined upwardly toward the right, as indicated by the dotted line position in Figure 6. In this manner, the brush structure of the main frame accommodates tilting of the car in either direction, which assures proper contact of brushes 51 and 52 at the upper and lower panels, respectively, of the car body. This is advantageous as assuring proper cleaning of the body of the car whether the side thereof be disposed vertically or at a slight inclination from the vertical in either direction.

A spray pipe 61 is disposed between the arms 14 of the main frame in parallel relation with and adjacent to brush shaft 50. At its upper end this pipe is connected by a ball joint 62 of known type (Figure 9) to a nipple 63 which has its upper end welded to and closed by the web or bight portion of arm 14. The lower end of spray pipe 61 is connected by a ball joint 64, similar to the ball joint 62, to the upper end of a nipple 65 which is welded to and extends through the bight portion of arm 15. A threaded coupling member 66, of known type, is provided at the lower end of nipple 65 for connecting thereto a hose leading from a suitable source of supply of water or washing solution under pressure. The flexibility of spray pipe 61, provided by the ball joints 64 therein, permits of relative movement of arms 14 and 15 for accommodating tilting of the brush structure to accord with tilting of the side of the car, above described.

Spray pipe 61 is disposed between the car body 75

brushes 51 and 52 of the main frame and a window brush 70 carried by the secondary frame. Brush 70 is disposed in overlapping relation to the brushes 51 and 52 and is suitably secured upon a brush shaft 71, which shaft is mounted at its lower end (Figure 10) in self-aligning roller bearings of known type carried by a bearing box 72. A splash guard 73 is secured to the shaft 71 and extends over the box 72 so as to prevent entry of moisture and foreign materials into the bearings, and a similar guard 74 is secured on stub shaft 53 above and adjacent bearing box 57. Bearing box 72 is bolted to a plate 75 at the upper end of a screw shaft 76 slidable through a sleeve 77 bolted to the outer end of lower arm 32 of the secondary frame. This shaft 76 is feathered to the sleeve 77 so as to be held against rotation while being slidable through the sleeve. A bevel gear 78 is rotatably mounted about shaft 76, between the upper end of sleeve 77 and a collar 79 at the upper end of an L-shaped arm 80 extending from the base of sleeve 77. Gear 78 is interiorly threaded and engages the screw shaft 76 for adjusting the latter vertically in accordance with rotation of the gear. A shaft 81 is rotatably mounted through arm 80, the inner end of this shaft extending into an opening in the sleeve adjacent the upper end of the latter. A hand wheel 82 is secured upon the outer end of shaft 81 for rotating the latter in desired direction. A bevel pinion 83 is secured on shaft 81 and meshes with bevel gear 78 for rotating the latter and adjusting screw shaft 76 when the hand wheel 82 is rotated. A shield 84, conveniently formed of sheet metal, is clamped between bearing box 72 and plate 75 and encloses the screw shaft 76, gear 78 and pinion 83, and associated parts, this shield being suitably slotted to accommodate arm 80 and arm 32 of the secondary frame in the vertical adjustment of the screw shaft. The bearing box 72 preferably contains self-aligning roller bearings of known type into which the lower end of shaft 71 extends, and a thrust collar 85 is disposed between the upper end of these bearings and the lower end of the hub of splash guard 73.

A bearing box 86 is bolted to the outer end of upper arm 28 of the secondary frame and carries self-aligning roller bearings of known type. A bevel gear 87 is rotatably mounted in the bearings in box 86 and slidably receives the upper end portion of shaft 71, this portion of the shaft being provided with suitable grooves 88 which receive corresponding splines formed in the hub of gear 87, whereby the shaft 71 is feathered to gear 87 for rotation therewith and is freely slid able through the gear. This connection between the shaft and the gear accommodates vertical adjustment of shaft 71 by means of the screw shaft 76 and associated parts, so that the window brush 70 is capable of vertical adjustment to suit the height of the windows of a car being washed.

Bevel gear 87 meshes with a bevel gear 90 secured on the outer end of a shaft 91 rotatably mounted in bearing boxes 92, containing roller bearings 93 of known type, these boxes being supported by standards 94 bolted to arm 28. A bevel gear 95 is secured upon the inner end of shaft 91 and meshes with a bevel gear 96 splined upon the lower end of shaft 21 and confined between the upper end of bushing 23 and a collar 97 suitably secured upon shaft 21. A bevel gear 98 is secured upon the upper end of shaft 21 and meshes with a bevel gear 99 secured upon a shaft 100 rotatably mounted in bearing boxes 101 carried

by standards 102 bolted to upper arm 14 of the main frame. A bevel gear 103 is secured upon the outer end of shaft 100 and meshes with a bevel gear 104 secured upon the upper end of stub shaft 59, there being a thrust collar 105 disposed between the lower end of the hub of bevel gear 104 and the upper end of the self-aligning roller bearings mounted in the box 60.

An electric motor 106 (Figure 1) is mounted upon the inner portion of arm 14 of the main frame, which arm is extended inwardly beyond support 1 to provide a mounting for this motor. This motor is connected to shaft 100 by means of a flexible coupling 107 of known type. The motor 106 and the shaft 100 and associated gears 103 and 104, shaft 71 of the window brush being driven through gears 99 and 98, shaft 21, gears 96 and 95, shaft 91, and gears 90 and 87. In this manner, the brushes of both of the frames are driven by shaft and gear means from the motor, this drive from the single motor being rendered possible by having the shaft 21 coaxial with the common pivotal axis of the main frame and the secondary frame.

An attaching strip 110 is secured to each arm of the main frame and projects beyond the sides of the arm. Tension springs 111, of equal length and strength, connect the ends of strip 110 to attaching clips 112 pivotally mounted at 113 on ears 114 welded or otherwise suitably secured to support 1 and projecting radially from the latter at diametrically opposite points thereof. Each of the clips 112 is provided with an upwardly extending tab 115 which cooperates with ear 114 to limit inward movement of clip 112 beyond substantial alignment with the associated ear 114, while permitting freedom of movement of the clip in the opposite direction about its pivot 113. An attaching member 116 is welded to sleeve 30 and is disposed to project beyond the sides of the secondary frame in the normal position of the latter. Attaching clips 117 are pivoted at 118 to the ends of member 116, each of these clips being provided with an upwardly projecting tab 119 cooperating with member 116 to limit inward movement of the tabs 117 beyond straight line position with member 116. These tabs are connected by tension springs 120, of equal length and strength, to ears 121 welded to a tubular frame member 122 extending between and welded to upper and lower arms 28 and 32, respectively, of the secondary frame, ears 121 being disposed in alignment and transversely of the arms of the secondary frame. Tension springs 111 normally hold the main frame in position to extend radially from the support 1, and when the machine is not in use the sleeve 30 is normally adjusted so that springs 120 hold the secondary frame in parallel relation to the main frame so as to be disposed therein and radial to support 1, as in Figure 3.

In Figures 4 and 5 I have illustrated two machines embodying my invention disposed at opposite sides of a track T for simultaneously washing both sides of a car C traveling along the track in the direction of the arrow and between the

machines. The machines are disposed at opposite sides of a shallow pit P over which the car travels, this pit having a central drain D. Spray pipes 125 and 126 are disposed at opposite sides 5 of the pit adjacent the entry and exit ends thereof, respectively, these spray pipes being at opposite sides of the support 1 of the machine and spaced therefrom a distance somewhat greater than the overall length of the main frame, including the brushes carried thereby. The spray 10 pipes have suitable spray arms 127 extending therefrom and disposed to project washing solution or rinsing water against the sides of the car. Conveniently, spray pipe 125 is connected to a suitable 15 source of supply of washing solution under pressure, which solution is projected onto the side of the car as it enters the space above the pit. The spray pipe 61 of the machine may be connected to a suitable source of supply of water or of washing solution, under pressure, and projects the solution or water onto the brushes of both of the frames. The spray pipe 126 is connected to a suitable source of supply of rinsing water under pressure and serves to rinse off the car after washing thereof. The support 1 is so 20 adjusted that brushes 51 and 52 of the main frame will contact the side of the car and be held thereagainst by spring pressure, this pressure being adjustable by appropriate adjustment 25 of the support. By turning the support of the upper machine in Figure 4 in a clockwise direction, the tension of springs 111, at the lower side of the machine in this figure, is increased, thus increasing the pressure exerted upon the brushes 30 51 and 52. By turning the support in the opposite direction, the pressure exerted on these brushes may be decreased. The window brush is yieldingly urged toward the side of the car by means of the spring 120 at the lower side of the 35 machine, as viewed in Figures 3 and 4, and the tension of this spring can be adjusted by rotating sleeve 30 in proper direction. Before the car enters between the two washing machines, the brushes occupy substantially the dotted line positions 40 of Figure 4. The entering car moves the brushes outwardly into the full line positions of Figure 4, in which positions the brushes are yieldingly held against the sides of the car and the windows, during which time the brushes are rotated and effectively wash the sides of the car, including the windows. When the car passes 45 beyond the brushes, it is rinsed off by water projected from the spray arms of the spray pipes 126. In Figure 7, I have shown one machine embodying my invention disposed between two adjacent tracks T for washing one side of a car traveling in one direction upon one track, and the other side of the car traveling in the opposite direction upon the other track. A shallow pit P' 50 is disposed between the two tracks and extends a short distance beneath each track for receiving the washing and rinsing solution and water, this pit being provided with suitable drains d. The washing machine is disposed centrally of the pit and spray pipes 130 are disposed at opposite sides of the washing machine and at the transverse center of the pit. These pipes are provided with spray arms 131 and are rotatable so as to be turned into position to project a washing solution or water onto the sides of a car traveling along 55 either track. In this figure of the drawings, the frames of the machine are so disposed that the brushes thereof contact the side and windows of a car traveling toward the right on the upper track. In this case, spray pipe 130 at the left

of the machine may be connected to a suitable source of supply of washing solution under pressure, pipe 130 at the right of the machine being connected to a suitable source of supply of rinsing water under pressure. By turning the support 1 through an arc of 180 degrees, in the direction of the arrow, the brushes are disposed to contact the side and windows of a car traveling in the direction of the arrow on the lower track, in which case the spray pipes occupy the dotted line positions of Figure 7, washing solution being supplied to the spray pipe at the right of the machine and rinsing water supplied to the spray pipe at the left of the machine. If it is desired to wash the side of a car traveling upon the upper track and in the direction opposite to the arrow, in Figure 7, the support 1 is rotated into such position that the brushes occupy the position indicated by the dot and dash lines of this figure, in which case washing solution may be supplied to the righthand spray pipe and rinsing water supplied to the lefthand spray pipe, the latter spray pipe being turned so as to project rinsing water against the side of the car beyond the brushes. Likewise, if it is desired to wash the side of a car traveling on the lower track oppositely to the arrow appearing in Figure 7, support 1 is rotated so as to bring the brushes into the positions indicated by the dot and dash lines of this figure, adjacent the lower track, in which case the lefthand spray pipe 130 receives washing solution and the righthand spray pipe receives rinsing water, this spray pipe being turned so as to project the rinsing water against the side of the car beyond the brushes. It will be clear from the above that my machine is capable of being used for washing the side of a car traveling in either direction upon either one of two tracks between which the machine is positioned, thus eliminating the necessity of providing two machines for washing the cars. In Figure 8 I have shown the two tracks provided with suitable switches S by means of which the car C, traveling in either direction upon either one of the tracks, may be transferred therefrom to the other track and moved along the latter in the opposite direction, one side of the car being washed during its travel upon the first track, and the other side of the car being washed during its travel along the second track. My invention thus eliminates the necessity of using two machines and the expense incident thereto. On the other hand, in cases where it is desired to use two machines, my machine is entirely suitable for such use and is capable of use for washing cars traveling in either direction upon a track having washing machines in accordance with my invention disposed at opposite sides of the track.

As above indicated, and as will be understood by those skilled in the art, changes in construction and arrangement of parts of my invention may be resorted to without departing from the field and scope of the same, and I intend to include all such variations, as fall within the scope of the appended claims, in my application in which the preferred forms only of my invention are disclosed.

What I claim is:—

1. In combination in a washing machine of the character described, a pivotally mounted main frame comprising upper and lower arms capable of limited independent movement about the pivot axis of the frame, a brush structure comprising a rotatably mounted articulated shaft connecting said arms and accommodating relative move- 75

ment thereof, a secondary frame pivotally mounted within and coaxially with the main frame, a brush rotatably mounted in the secondary frame, means for driving said shaft and said brush, and 5 a spray pipe connecting the arms of the main frame and disposed to project fluid onto the brushes of both frames, said pipe being flexibly connected to the arms of the main frame for accommodating relative movement of said arms. 10 2. In combination in a washing machine of the character described, a rotatable support, means for rotating said support and locking it in adjustment, a main frame pivoted on the support for movement on an axis parallel to the axis of rotation of the latter, a secondary frame pivoted on the support coaxially with the main frame, brushes rotatably mounted on said frames, means for driving said brushes, a member mounted for rotation about the pivot axis of the secondary frame, means for rotating said member and locking it in adjustment, tension springs connecting the main frame at opposite sides thereof to the support at opposite sides of the latter, and tension springs connecting the secondary frame 25 at opposite sides thereof to said member at opposite sides of the latter. 3. In combination in a machine for washing cars and vehicles of like character, a support mounted to turn on a vertical axis, a main brush frame pivoted on the support on a vertical axis, a brush rotatably mounted in the frame, a secondary frame pivotally mounted within and coaxial with the main frame, a brush rotatably mounted in the secondary frame, the secondary 30 frame and the brush mounted therein being movable through the main frame in either direction about the pivotal axis of the main frame, said support being rotatable in both directions and through an arc of approximately 180° and the

brush frames normally extending from the support substantially radial thereto, and means for driving said brushes. 5

4. In combination in means for washing cars and like vehicles, a track defining a path of travel for vehicles to be washed, a support adjacent the track at one side thereof, a frame mounted on the support for swinging movement on a vertical axis, a brush rotatably mounted in the frame, means for driving said brush, and yielding means normally holding said frame substantially radial to the support, said support being rotatable on a vertical axis for disposing the frame at either side of said axis and in the general direction of the track. 10

5. In combination in means for washing cars and like vehicles, two adjacent and parallel tracks defining paths of travel for vehicles to be washed, a brush frame, a brush rotatably mounted therein, means for driving said brush, and means between the tracks for supporting said frame and disposing it in position adjacent either track and extending from the support in either direction along and in the general direction of the track. 15

6. In combination in means for washing cars and like vehicles, two adjacent and parallel tracks defining paths of travel for vehicles to be washed, a support between the tracks, a brush frame mounted on the support for swinging movement on a vertical axis, yielding means normally holding the frame in predetermined relation to the support, a brush rotatably mounted in said frame, said support being turnable on a vertical axis and through a complete rotation for disposing the frame in position adjacent either track and extending from the support in either direction along and in the general direction of the track. 20 25 30 35

CLYDE P. ROSS.
